UNITED STATES PATENT OFFICE

116,727

DESIGN FOR A WATER COOLING TOWER

Amel A. Stillger, Huntington Park, Calif., assignor to The Fluor Corporation, Ltd., Los Angeles, Calif., a corporation of California

Application June 20, 1939, Serial No. 85,579

Term of patent 14 years

To all whom it may concern:

Be it known that I, Amel A. Stillger, a citizen of the United States, residing at Huntington Park, California, in the county of Los Angeles and State of California, have invented a new, original, and ornamental Design for a Water Cooling Tower, of which the following is a specification, reference being had to the accompanying drawing forming a part thereof.

The figure is a perspective view of a water cooling tower embodying my new design, the tower being of symmetrical proportions.

I claim:

The ornamental design for a water cooling tower, as shown and described.

AMEL A. STILLGER.
